(57) **CLAIM**

The ornamental design for an electric full body fitness equipment as shown and described.

DESCRIPTION

FIG. 1 is a top perspective view of an electric full body fitness equipment;

FIG. 2 is a bottom perspective view thereof;

FIG. 3 is a front elevational view thereof, a rear elevational view is not shown because it is a mirror image of the front elevational view;

FIG. 4 is a top plan view thereof;

FIG. 5 is a bottom plan view thereof; and,

FIG. 6 is a right-side elevational view thereof, a left-side elevational view is not shown because it is a mirror image of the right-side elevational view.

The broken lines form no part of the claimed design.

1 Claim, 2 Drawing Sheets
